J. KARITZKY

BOLT ANCHOR

Filed April 12, 1922

John Karitzky INVENTOR
BY Alan S. Johnson ATTORNEY

UNITED STATES PATENT OFFICE.

JOHN KARITZKY, OF GARWOOD, NEW JERSEY, ASSIGNOR TO HENRY B. NEWHALL, EXECUTOR OF HENRY B. NEWHALL, SR., DECEASED.

BOLT ANCHOR.

Application filed April 12, 1922. Serial No. 551,890.

To all whom it may concern:

Be it known that I, JOHN KARITZKY, a citizen of the United States, residing at Garwood, in the county of Union and State 5 of New Jersey, have made certain new and useful Improvements in Bolt Anchors, of which the following is a specification taken in connection with the accompanying drawings.

10 My invention relates to a bolt anchor in which the expansible shield is provided with a conical bore, and an expanding member preferably in the form of a conical nut, and preferably free from lugs or projections. The expanding member is adapted to be held within the conical bore of the shield by swaging, bending or compressing a portion of the shield into engagement with co-operating surfaces on the expanding member or cone, said surfaces being preferably in the form of recesses within the cone, thereby obviating the necessity of employing additional members to hold the parts together during packing, handling and transportation.

15 My invention further relates to such a bolt anchor in which the shield is provided with one or more longitudinally extending slots, extending from the exterior of the shield to the bore, said slots being shorter than the length of the shield. This leaves both ends of the tubular shield closed or unsevered. I preferably extend the longitudinally extending slot or slots nearer to the inner end of the shield than to the outer end, leaving enough metal however to form a fin, or fins of sufficient strength to resist the ready opening or spreading of the shield, which would permit the expanding member 20 to drop out of the shield, but not of sufficient strength to prevent fracture or rupture of the fin or fins in the spreading of the shield, when it is expanded in operation by the expanding member.

25 My invention further relates to such a bolt anchor in which the shield and cone, or expanding member, are formed of materials of different strength, the expanding cone being of greater hardness and less ductility than the shield.

30 My invention further relates to forming the shield of some ductile material, as aluminum, brass, fibre lead or an alloy, so that when it is expanded the metal will flow,

more or less, into the irregularities and 55 voids of the wall of the hole. The expanding cone is formed of some harder material, as for example, iron, which may or may not be galvanized.

35 My invention further relates to forming, 60 as for example by casting, one or more tits upon the exterior surface of the expansible shield and forming a cooperating hole or holes on the exterior surface of the cone, or other expanding member. In assembling the 65 parts for packing, handling and transportation the holes in the expanding member are brought beneath the tits, when a soft blow upon the tits will cause the metal of the shield to flow, more or less, into the holes 70 in the cone, thereby locking the shield and cone together against accidental disengagement.

40 My invention further relates to certain 75 combinations, details of construction, and articles of manufacture, which will be more fully hereinafter described and pointed out in the claims.

45 In the accompanying drawings the same 80 reference numerals refer to similar parts in the several figures.

50 Fig. 1 is a vertical section showing my 85 bolt anchor assembled and in operative position within a hole in the wall ready to be expanded;

55 Fig. 2 is a vertical section, similar to Fig. 1, showing the parts when expanded;

60 Fig. 3 is a vertical section similar to Fig. 2, showing the same bolt anchor expanded within a larger hole, and showing 90 the fin at the inner end ruptured so as to permit greater expansion of the shield;

65 Fig. 4 is a side elevation, partly in longitudinal section, of the preferred form of 95 my shield;

70 Fig. 5 is a plan view of the shield;

75 Fig. 6 is an end view of the shield shown in Fig. 5;

80 Fig. 7 is a cross section on the line 7—7 of Fig. 8;

85 Fig. 8 is a plan view of the expanding member, shown as a cone;

90 Fig. 9 is a side elevation partly in longitudinal section showing the manner of securing the shield and cone together.

95 Prior to my invention, it has been old to use an expansion shield formed of a plurality of parts and conical nuts, provided

with lugs or projections to cooperate with special engaging surfaces on the shield. To assemble these parts for shipping, it is necessary to bring the lugs or projections upon 5 the cone member into cooperating position with the special engaging surfaces on the shield, and then secure the parts together by some binding member, as for example, wire wrapped on the exterior of the shield, or 10 spring rings. This method is very expensive and unsatisfactory, for considerable time is taken in assembling each of the bolt anchors.

It is found in practice that the vibration, 15 jostling in transportation, and handling will cause many of the constituent parts of the bolt anchors to become separated, so that the dealer, before putting them upon his shelves, has to go over the shipment to see 20 whether or not all the bolt anchors are properly assembled and held together, and to reassemble such as have become separated during transit. This takes additional time, adds to the expense and is a considerable 25 annoyance to the dealer.

Prior to my invention it was also old to use cone nuts with tubular ductile lead sleeves having a tapered interior bore and 30 walls of uniform circumferential thickness, without grooves or slots to facilitate or even to permit expansion by means of a bolt and wrench.

Such expansions as I have just described required the use of special tools to drive the 35 lead shield down over the cone nut. They required the heavy blows of a hammer to caulk them down over the cone nuts to drift them out or expand them.

By means of slots and fins provided in my 40 shield, as hereinafter described, I overcome the disadvantages of the shield made of a plurality of parts provided with lugs, springs, etc., and also overcome the objectionable features of the lead sleeves which required caulking tools and the laborious work 45 of caulking them in the wall with a hammer.

By my invention I obtain a bolt anchor, which can be manufactured at minimum expense; requires no additional member to secure the parts together; can be assembled with great speed and accuracy, and after being once assembled the parts stay assembled and will not become disconnected 50 during transportation or handling, so that all the annoyances and expense incident to the manufacture and sale of the present bolt anchors are avoided.

My bolt anchor consists essentially of a 60 shield 1 and an expanding member 2. This expanding member is preferably formed as a conical nut and provided with a conical surface 3 devoid of all lugs or projections so that it can be readily manufactured in an 65 ordinary screw machine at minimum ex-

pense. It is provided with interior screw threads 4 to cooperate with the threads 5 upon the bolt 6. For purposes of illustration I have shown these screw threads 4 within the cone 2 and the screw threads 5 70 upon the bolt 6 as machine screw threads. Though, of course, they may be varied so that a lag screw or other similar member may be employed to operate the cone 2.

The expandible shield 1 is provided with 75 an axial bore 7 having a tapered or flaring portion 8 starting from about the point 9, Fig. 4. I also provide the shield with one or more slots 10, 10. These slots extend 80 entirely through from the exterior surface of the shield to the axial bore 7. The slots, however, are shorter than the length of the shield 1 and preferably located as shown in Fig. 5, extending a little nearer to the inner end 11 than the outer end 12 of the shield. This leaves both ends of the shield 85 continuous or unsevered. It is not desired to expand the outer end 12 of the shield as the same would have a tendency to crack, mar or crumble the outer surface 13 of the 90 wall 14. The inner end 11 is provided with the fins 15, 15, making that end of sufficient strength to prevent accidental fracture and opening up of the shield, but not of sufficient strength to resist the ready 95 opening and spreading of the shield in operation by the cone 2 being caused to move along the conical or flared portion 8 of the axial bore toward the work 16.

To insure that the expanding member or cone 2 will not become disengaged from the shield 1, due to vibration or jostling in transportation and handling, I form cooperating locking surfaces between the shield 1 and the expanding member or cone 2. These 100 engaging or locking surfaces are only brought into their operative position after the cone or expanding member 2 has been seated within the conical portion 8 of the axial bore ready for shipment. Of course, 105 various forms of interlocking surfaces may be used. I have shown for example, the shield 1 provided with tits 17, 17 which are preferably cast on the shield 1. The cone or expanding member 2 is provided with one or more recesses 18, 18 which when the parts 110 are assembled ready for shipment are so inserted that they are beneath the tits 17, 17. By then swaging, pressing, hammering or otherwise exerting pressure upon the tits 17, the metal immediately underneath said 115 tits is caused to flow into said recesses 18, 18 as shown in Fig. 9, the parts thereby being firmly locked together for handling, packing and transportation. When these tits are 120 reduced as above explained, their upper surfaces will lie substantially flush with the exterior surface of the shield, so that the bolt anchor can be put into a correctly drilled 125 hole 19 for that particular sized bolt anchor.

The exterior surface of the shield 1, adjacent to the end 12, may be provided with the ribs 20, 20.

After the bolt anchor, including the shield 1 with its cone 2, is inserted in the hole 19, the machine bolt 6 is passed through the opening in the work 16 until its threads 5 cooperate with the female threads 4 in the cone 2. By rotating the head 21 of the bolt the cone 2 is caused to move up the flaring or conical axial bore 8 and in doing so that portion of the metal of the shield which has been pressed into the recesses 18, 18 in the cone will either be forced out of said recesses or be broken off depending upon the material employed. In a properly sized hole 19, the fins 15, 15 will simply stretch and permit the shield to be firmly pressed outward into engagement with the surface of the hole 19.

It is considered good practice by engineers and mechanics, both from the standpoint of workmanship and economy to drill the hole of as small a diameter as possible to cause the shield to fit snugly in the hole before expanding. In an accurately drilled hole immediate and powerful contact is had between the exterior of the shield and the walls of the hole when the threaded bolt 30 starts to draw the nut outwardly compressing the ductile metal of the shield 1 between the advancing nut and the work at the surface of the hole. This causes the lead or ductile shield to flow into the interstices found in the wall surrounding the hole. Such interstices are formed in the walls of holes drilled in manufactured stone or brick and in natural stone by the dislodgement of pebbles, coarse sand and hard particles constituting the mass.

Used in an accurately drilled hole the ductile shield is compressed or shortened between the nut and the work and at the same time the diameter of the shield is increased 45 uniformly in all directions limited only by its powerful contact with the contour of the hole. Under such conditions the fins 15, 15 will simply stretch and will not ordinarily be fractured, see Fig. 2.

When, however, a hole is drilled oversize, Fig. 3, the shortening of the shield and the increasing of its diameter is carried to a greater degree than in the closer fitting hole and the cone nut 2 is drawn further toward 55 the work 16. Under such conditions the expansion of the shield is facilitated by the fracturing of the fins 15, 15, see Fig. 3.

In either a close fitting hole or an oversize hole the slots perform the important 60 function of facilitating the expansion of the shield by permitting stretching of the fins in a close fitting hole and by permitting them to be broken in an oversized hole. If the fins were omitted the separated end of the 65 shield would be forced apart in transit

allowing the nut to drop out, with the disadvantages previously pointed out.

In positioning the bolt anchor, I have shown in Figs. 1 and 2 the operation when the hole 19 in the wall or other suitable support 14 is properly drilled to receive it; and in Fig. 3 the operation when the hole 19 is larger than necessary resulting in fracturing the fins 15, 15. For purposes of illustration the clearance of the shield within the hole 75 and its subsequent expansion is somewhat exaggerated.

By my invention in which I preferably employ a ductile shield 1, the powerful expansion exerted by the iron conical nut 3 causes the metal of the shield to flow more or less as shown in Figs. 2 and 3, filling up all the inequalities or voids on the interior of the hole 19. By forcing the metal to flow into these inequalities I obtain a particular 80 strong union or hold with the wall or other suitable support.

Having thus described this invention in connection with an illustrative embodiment thereof, to the details of which I do not desire to be limited, what is claimed as new and what is desired to secure by Letters Patent is set forth in the appended claims.

What I claim is:—

1. An assembled bolt anchor comprising 95 an expandable ductile shield provided with compressible ductile locking means to engage with and hold expanding means, expanding means mounted in the ductile shield and having means to cooperate with the compressible ductile locking means, so that the parts will not become separated in handling, storage and transportation.

2. An assembled bolt anchor comprising 100 an expandable ductile shield provided with compressible ductile locking means to engage with and hold an expanding cone of relatively strong material mounted in the ductile shield and held therein by the compressible ductile locking means so that the parts will not become separated in handling, 105 storage and transportation.

3. An assembled bolt anchor comprising 110 an expandable shield, an expanding member, and breakable means holding the expanding member within the expandable shield and adapted to be broken only when the expanding member expands the shield.

4. An assembled bolt anchor comprising 115 an expandable shield, an expanding member, and ductile means holding the expanding member within the expandable shield and adapted to be compressed only when the expanding member expands the shield.

5. An assembled machine expansion comprising 120 an expandable shield having an interior conical bore, an expanding cone mounted in the bore, and ductile means engaging with the cone and the shield adapted to hold the parts together so that they will 125

not become separated in handling, storage and transportation.

6. An assembled bolt anchor comprising a ductile shield provided with one or more ⁵ tits, an expanding member mounted in the shield and adapted to be held therein by said tits so that the parts will not become separated in handling, storage and transportation.

10 7. An assembled bolt anchor comprising a ductile shield provided with one or more

tits on its exterior, a cone mounted in the shield and provided with one or more recesses, the cone being adapted to be held in the shield by causing the metal of the ¹⁵ shield adjacent to the ribs or tits to flow into the recess or recesses in the cone.

JOHN KARITZKY.
